Primary Examiner — Robin V Webster(74) *Attorney, Agent, or Firm* — Michael Best & Friedrich LLP(57) **CLAIM**

I claim the ornamental design for a shower and speaker assembly, as shown and described.

DESCRIPTION

FIG. 1 is a side view of a shower and speaker assembly; and, FIG. 2 is a front perspective view of the shower and speaker assembly shown in FIG. 1.

Any broken line showing of the environment is for illustrative purposes only and forms no part of the claimed design.
